UNITED STATES PATENT OFFICE.

WILLIAM W. SLEIGHT, OF CHICAGO, ILLINOIS.

DESIGN FOR A BOLT FOR WINDOW-FRAMES.

55,438.

Specification for Design.

Patented June 8, 1920.

Application filed September 29, 1919. Serial No. 327,335. Term of patent 14 years.

To all whom it may concern:

Be it known that I, WILLIAM W. SLEIGHT, a citizen of the United States, and resident of Chicago, in the county of Cook and State of Illinois, have invented a new, original, and ornamental Design for Bolts for Window-Frames, of which the following is a specification, reference being had to the accompanying drawings, forming a part thereof.

In the drawings:

Figure 1 is a plan view of the said bolt for window frames.

Fig. 2 is an edge view thereof.

Fig. 3 is a front end view of the same.

My invention particularly refers to the construction of the head of said bolt for window frames and it comprises an oblong

head and a tenon projecting therefrom which is T-shaped in cross-section and is elongated vertically or in the direction of the major axis of the oblong head.

A flat bolt which forms no part of the design it is desired to protect, projects from the rear of said head. Its edges are provided with serrations and its rear end is provided with vertically projecting lugs, that project upward and downward therefrom to an equal extent and are disposed in a vertical plan parallel to the vertical plan of the rear of the head.

I claim:

An ornamental design for a bolt for window frames as shown and described.

WILLIAM W. SLEIGHT.
